UNITED STATES PATENT OFFICE

PERCIVAL S. TICE, OF CHICAGO, ILLINOIS, ASSIGNOR TO STEWART-WARNER CORPORATION, OF CHICAGO, ILLINOIS, A CORPORATION OF VIRGINIA

ELECTROMAGNETIC FUEL PUMP

Original application filed February 13, 1928, Serial No. 253,974. Divided and this application filed August 1, 1931. Serial No. 554,513.

This application is a division of my pending application Serial Number 253,974, filed February 13, 1928. The specific purpose of the present invention is to provide an improved construction of electromagnetic pumping device which is shown in suitable form for pumping fuel to an internal combustion engine. It consists in the elements and features of construction shown and described as indicated in the claims.

10 In the drawings:

Figure 1 is a diagrammatic view showing the installation of the electromagnetic pump for supplying fuel to an internal combustion engine.

15 Figure 2 is an axial section of the pump structure showing also its connection for liquid-inflow from the liquid source and discharge to the place of use, said place of use being, as shown, the governed level fuel chamber of an engine carburetor.

Figure 3 is a section at the line 3—3 on Figure 2.

20 Figure 4 is a detail section at the line 4—4 on Figure 3 on an enlarged scale for showing the alternating switch.

Figure 5 is a wiring diagram for showing the circuit connection with the switch shown in Figure 4.

25 Figure 6 is a detail section at the line 6—6 on Figure 2.

Figure 7 is a section at the line 7—7 on Figure 6.

In the embodiment of the invention to be covered by this divisional application, the electromagnetic pumping element comprises an energizing circuit winding, 200, wound between iron retaining rings or spool heads, 201, 202, upon a hollow core member, 203, 30 whose cavity from one end to a point somewhat past the middle of the length constitutes a piston chamber, 204, in which there is fitted pistonwise an armature element, 205, the remaining portion of said cavity, which is somewhat less than half the axial extent of the encompassing circuit winding, being occupied by a fixed magnet pole piece, 206, to which the armature piston, 205, is attracted when the circuit is closed through 35 the circuit winding, 200. A spring, 205a, is

provided reacting on the armature piston for restoring it to normal position, withdrawn from the pole piece, 206, when the circuit is interrupted by the action of the switch to be now described.

At the end of the core member opposite the pole piece, 206, there is mounted a segmental annular insulating plate, 207, which serves to stop the outwardly spring-caused stroke of the armature piston. On said insulating plate, 207, there is mounted a switch lever, 208, pivoted at one end as seen at 209 in Figure 3, on a bracket, 210, mounted fixedly on said insulating plate, 207, and in contact with a binding post, 210a, to which is attached the circuit wire, 211, which leads from the ignition switch seen at M in Figure 5.

Said switch lever extends across the axis of the core member and carries at its free end a roller, 212, which at rest position of the parts, when no current is passing through the magnet circuit winding, and the armature piston is accordingly thrust by the spring, 205a, against the inner side of the insulating plate, 207, rests against the inner side of a double cone boss, 213, of insulating material having a hollow stem, 214, by means of which it is mounted centrally in the armature piston, 205, and cooperates with the pin, 206a, 40 which projects rigidly from the pole piece, 206, into said hollow stem for guiding the armature piston, from which said double cone boss projects past the insulating plate, 207. At this position of the switch lever it is in 45 contact with the contact member, 215, to which is attached the circuit wire forming the circuit winding, 200, whose inner end is grounded in any convenient manner; and in this position of the switch it closes the circuit 50 through said circuit windings for energizing the magnet pole piece. The roller, 212, is journaled in the ends of the two parallel arms 208a, 208a, of the switch lever, 208, and has one of its journal bearings slotted as seen 55 at 208b Figure 5 to permit the roller journaled at its end to vibrate toward and from the double-coned boss, 213; and a stretched spring, 216, connected to that end of the roller journal and at the other end to the bracket, 60

210, operates for holding the roller stressed against the double cone with the effect that when the armature piston is pulled inward by the attraction of the pole piece upon the closing of the circuit through the ignition switch by the governing switch, not shown, energizing the circuit winding, 200, the roller being crowded out to the apex of the double cone is retracted on the outer cone slope and the 10 switch lever, 208, is thus swung over to circuit-breaking position where it is stopped against the insulating plate, 207.

Thereupon the spring, 205a, retracts the armature piston to the initial position causing 15 opposite action of the cooperating double cone and roller, i. e., swinging the switch lever back to the circuit-closing position; and thus the armature piston is reciprocated rapidly so long as the circuit is closed through the 20 governing switch and interrupted only by the alternating switch above described.

The electromagnetic pumping device thus far described is fitted snugly in a cylindrical cavity of the casing, 220, with one open end 25 of which the pumping device is flush, the cavity of the casing being counterbored the length over-all of the pumping device, leaving at the inner end of the cylindrical cavity a chamber, 221, in which the alternating 30 switch device above described is situated. The casing, 220, has an exteriorly projecting hollow boss, 222, affording a duct, 222^x, said boss and duct extending the entire height of the casing at the side at which the chamber, 35 221, is situated, and extending also around the lower right-hand corner and along the side of the casing, as seen at 223, and open at the end at which the pumping device is flush with the casing as above mentioned.

40 At the upper side the casing has a hollow boss, 224, affording a duct, 224^x, open at the same end as the duct, 222^x, of the boss, 222. A port, 225, affords communication of the chamber, 221, with the duct, 222^x, at the upper 45 end of the latter; and below that port there is interposed in the duct, 222^x, a check valve, 226, open for fluid flow toward the port, 225, and thereby into the chamber, 221; and from the upper side of that chamber a port, 227, 50 controlled by a check valve, 228, affords communication with the duct, 224^x, in the boss 224, the valve, 228, opening of flow from the chamber into the duct, 224^x, and seating against reverse flow.

55 In the drawings this pumping device as a whole is shown connected for supplying fuel to the governed level fuel chamber of an engine carburetor, said governed level fuel chamber being indicated at 100 in Figures 2 and 6; and the connection for inflow from the liquid source and discharge to said governed level chamber may be understood from Figure 2, as will now be described, the inflow from the liquid source being by a pipe, 101, 60 through a strainer, 102, past a check valve,

103, to a pipe, 104, extending upwardly in the chamber, 100, said pipe having connection at 105 with the duct, 222^x, which leads to the inflow check valve, 226, and having connection by way of a check valve, 107, with the flow passage, 206^x, of the core member, 206.

70 The pipe, 104, discharges at its upper end, as seen at 109, in the upper part of the chamber, 100, said discharge being controlled against backflow by a check valve, 110; and the duct, 224^x, also discharges into the upper part of the chamber, 100, as seen at 111, backflow being prevented by the check valve, 228, already described.

75 I claim:

1. In an electromagnetic pumping apparatus, in combination with a pump cylinder and piston therein, an electromagnetic device comprising a fixed core of magnetizable metal, electric circuit windings encompassing 80 said core for magnetizing the same when the windings are electrically energized; a switch device for connecting said windings with the source of current, the pump cylinder and piston being axially aligned with the electromagnet core and windings, the piston being 85 of metal suitable to cooperate as an armature with the fixed core of the electromagnet, and having mechanical connections for operating the switch to open the circuit by its movement 90 responsive to the attraction of the magnet core and to close the circuit by the reverse movement, and a spring reacting on the armature piston to cause such reverse movement.

95 2. In the construction defined in claim 1, 100 the pump cylinder being extended from one end of the magnetizable core, and the circuit windings being extended to encompass said cylinder continuously with the windings about the core.

105 3. In combination with the construction defined in claim 1, a casing in which the electromagnetic device is contained having a chamber at the part thereof in which the pump cylinder is located, said chamber having a liquid inlet and outlet and check valves 110 controlling the same for inflow and outflow respectively, and seating against reverse flow.

115 4. In the construction defined in claim 1, the pump cylinder being joined fluid-tight to the magnetizable core, and said core having an aperture extending longitudinally through it for affording fluid inlet and outlet to the pump cylinder in the reciprocation of the armature piston, whereby the structure is 120 adapted to be connected for pumping at the side of the magnet core opposite that at which the cylinder and piston are located.

125 5. In combination with the construction defined in claim 1, a casing in which the electromagnetic device is contained having a chamber at the end at which the cylinder and piston are located, said chamber having liquid inlet and outlet connections and check valves 130 controlling said inlet and outlet openings for

inflow and outflow respectively, and seat-
ing against reverse flow, the pump cylinder
member being joined liquid-tight to the mag-
netizable core, and said core having an aper-
ture from end to end to afford fluid inflow
and outflow to the cylinder responsive to the
reciprocation of the piston therein, whereby
the structure is adapted for pumping connec-
tion at the end opposite the cylinder and pis-
ton and thereby becomes a double-acting
pump.

10 In testimony whereof, I have hereunto set
my hand at Chicago, Illinois, this 13th day
of July, 1931.
